UNITED STATES PATENT OFFICE.

JOHN H. PORTER AND JOHN HUGH DALY, OF JACKSON, MICHIGAN.

GASOLINE-VAPOR CONDUCTOR.

SPECIFICATION forming part of Letters Patent No. 349,953, dated September 28, 1886.

Application filed March 31, 1886. Serial No. 197,368. (No model.)

To all whom it may concern:

Be it known that we, JOHN H. PORTER and JOHN HUGH DALY, citizens of the United States, residing at Jackson, in the county of Jackson and State of Michigan, have invented certain new and useful Improvements in Gasoline-Vapor Conductors; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to devices for use in gasoline-stoves, and is intended to carry off the obnoxious vapors and smells which arise from the flames of this class of stoves.

It consists in the novel features hereinafter described, and specifically set forth in the claim.

20 In the accompanying drawings we have fully illustrated our vapor-conductor, Figure 1 being a perspective showing it applied to a gasoline-stove, and Fig. 2 being a vertical cross-section of the conductor removed.

25 Referring to the drawings by letter, A represents a gasoline-stove of any ordinary construction. B is the vapor-conductor, which is constructed of sheet metal, and consists of a back, C, top D, sides E, and bottom flange, F, all formed from a single piece of sheet metal. The top D is bent downward slightly at its front edge, as shown at D', so as to direct the 30 ascending vapors and products of combustion toward the escape G, secured to the center of the top D and connected to the flue or chimney by a pipe, H. The sides E have their

upper edges joined to the end of the top by soldering or any equivalent means. They diminish in width toward the bottom, as clearly shown, where they are connected to the bottom flange, F, in a similar manner. This flange F rests upon the rear edge of the stove and is provided with two or more bolt-holes, 40 45 J, through which and openings in the top of the stove bolts are passed to secure the conductor in position.

The advantages of our device will be readily appreciated. The obnoxious vapors and 50 smells generated by the heat of the stove will be drawn through the escape-flue G and will pass out through the chimney instead of expanding and permeating the air of the room and building which contains the stove. 55

Having thus described our invention, what we claim, and desire to secure by Letters Patent, is—

The herein shown and described conductor for vapor-stoves, consisting of a single piece 60 of sheet metal formed into the back C, the top D, provided with a depending front edge, D', the bottom or flange F, and the sides E uniting the top and bottom and widening as they recede from the bottom and approach the top, 65 which latter is apertured and provided with an escape-flue, G, substantially as and for the purposes described.

In testimony whereof we affix our signatures in presence of two witnesses.

JOHN H. PORTER.
JOHN HUGH DALY.
